Baker & Brown,
ATTORNEYS.

UNITED STATES PATENT OFFICE.

KAMEZO SEKO, OF EAST SAN PEDRO, CALIFORNIA.

HOLDER.

Application filed October 30, 1922. Serial No. 597,806.

This invention relates to holders, and particularly to cigarette holders. The invention contemplates the provision of means which function similarly to the bowl of a pipe, in that the said means is adapted to wholly confine and maintain a cigarette within the same effectively preventing loss of ashes, as well as tobacco from the cigarette casing or covering. The invention has 5 for an object the provision of a holder which will permit the cigarette smoker to lay the holder with its cigarette therein on a table, or in any place desired, without fear of the cigarette, when burning, damaging 10 the table, or setting fire to objects. Another object is the provision of a holder which prevents ashes from being dislodged from the cigarette within the holder, and which ashes, as well as any stub of the cigarette 15 may readily be removed from the holder, as desired. Another object is the provision of a holder which will allow the entire cigarette to be burned without any wasted stub.

25 Other objects will readily be appreciated by any cigarette user, such as preventing a staining of the fingers from the nicotine in the cigarette smoke.

With the above and other objects in view, 30 the invention consists in the novel and useful provision, formation, construction and inter-relation of the various parts, members and features, all as shown in certain embodiments in the accompanying drawing, described generally and finally pointed out 35 more specifically in the claims.

In the drawing:

Figure 1 is a perspective view of a cigarette holder shown as incorporating the invention in one embodiment;

Figure 2 is a cross sectional view of certain features of the holder shown in Figure 1, and showing the general construction of the same;

Figure 3 is a modified form of construction of the holder shown in Figures 1 and 2; and,

Figure 4 is a cross sectional view of the cigarette holder taken on the line 4-4 of Figure 2, and looking in the direction of the appended arrows.

Corresponding parts in all the figures are designated by the same reference characters.

55 Referring specifically to the drawing, A designates one form of holder, and B a sec-

ond form of holder. The holder A shown in Figures 1, 2 and 4 includes a stem member 1, and a casing portion 2 adapted to confine a cigarette a within the same, as illustrated in Figure 2. The casing 2 may be conveniently held to the stem 1 as by grooving the stem at 3 and notching an end of the casing 2, as shown at 4 for detachable reception within said groove 3. In the embodiment shown in Figures 1, 2 and 4, the casing is of greater diameter than the normal diameter of a cigarette a, and within said casing is a foraminous member b which is spaced from the casing 2 and may be 60 concentric within said casing and held in spaced relation to the casing by turning the ends of said member at an angle, as illustrated at 5 and 6. The casing 2 is perforated as shown at 7 so that the cigarette 70 a when burning is at all times exposed to the atmosphere. The casing 2 may be provided with a cap 8 which is likewise provided with a plurality of perforations 9, and which cap 8 may be detachably held to 75 the casing 2 as by means of a chain 10. It is to be noted that the cap 8 prevents any dislodgment of the cigarette from the casing. The end of the casing which is joined with the stem may be provided with a webbing 80 as shown in Figure 4 at 11, which will prevent endwise movement of the cigarette into the stem 1 and serve and maintain the cigarette in position within the member b.

The modified form of holder illustrated by 85 B in Figure 3 consists in forming the casing 12 with the stem 13 so that one is a continuation of the other. The part 12 is provided with a series of perforations 14 and likewise may carry a cap 15 also perforated as shown 90 at 16. The part 14 may be provided with a foraminous member b, if desired, or the member b may be dispensed with and the cigarette a placed within the part 12, as shown in Figure 3. In this connection the 95 stem 13 has the usual bore 17 extending therethrough, and the shoulder 18 between the stem and the part 12 acts to prevent endwise movement toward the stem.

The casing 2 or the part 12 may be formed 105 of various material, such as aluminum, meer-schaum and other compositions depending upon the use and value of the holder and the individual tastes of its user.

It is obvious that various changes and 110 modifications and variations may be made in departure from the specific showing which

is illustrative only in practicing the invention, and that all of said changes may be made within a fair interpretation of the invention as set forth by the appended claims.

5 Having thus disclosed my invention, I claim and desire to secure by Letters Patent:

1. A holder for cigarettes and the like, including a stem and a casing member adapted 10 to house a cigarette; and means within said casing for isolating the said cigarette from the inner wall of said casing during combustion of the cigarette therein; said means including an annular foraminous member, and 15 a webbing at one end of the casing for limiting movement of the cigarette therein in one direction.
2. A holder for cigarettes and the like, in-

cluding a stem and a casing member adapted to house a cigarette; and means within said 20 casing for isolating the said cigarette from the inner wall of said casing during combustion of the cigarette therein; said means including an annular foraminous member, and a webbing at one end of the casing for limiting 25 movement of the cigarette therein in one direction; said stem being adapted to be received in part within said casing and said casing being formed with a depressed portion adapted to engage a notch in the said 30 stem to effect an interlocking engagement therewith.

In testimony whereof, I have signed my name to this specification.

KAMEZO SEKO.
